Primary Examiner — Mitchell Siegel(74) *Attorney, Agent, or Firm* — Dunlap Bennett & Ludwig PLLC; Brendan E. Squire(57) **CLAIM**

The ornamental design for a double Ferris wheel, as shown and described.

DESCRIPTION

FIG. 1 is a perspective view of the double Ferris wheel showing my new design;

FIG. 2 is a right side view thereof; the left side being a mirror image thereof;

FIG. 3 is a front view thereof;

FIG. 4 is a rear view thereof;

FIG. 5 is a bottom view thereof; and,

FIG. 6 is a top view thereof.

The broken lines shown in the drawings illustrate portions of the double Ferris wheel that form no part of the claimed design.
